Primary Examiner — Jonathan J Han

(57) **CLAIM**

The ornamental design for a shoe soles, as shown and described.

DESCRIPTION

FIG. 1 is a perspective view of a shoe sole showing my new design;

FIG. 2 is a top plan view thereof;

FIG. 3 is a bottom plan view thereof;

FIG. 4 is a left side elevation view thereof;

FIG. 5 is a right side elevation view thereof;

FIG. 6 is a front elevation view thereof;

FIG. 7 is a rear elevation view thereof; and,

FIG. 8 is an enlarged view of the shoe sole labeled “8” in FIG. 6.

The broken lines in FIG. 3 show portions of the shoe sole that form no part of the claimed design.

The broken line circle shown in FIGS. 6 and 8 show an area of enlargement and the broken line circle form no part of the claimed design.

1 Claim, 8 Drawing Sheets(56)
